UNITED STATES PATENT OFFICE

VICTOR W. GIDEON, OF CHICAGO, ILLINOIS, ASSIGNOR TO WILSON-JONES COMPANY, A CORPORATION OF MASSACHUSETTS

POSTING TRAY

Original application filed December 14, 1927, Serial No. 239,882. Divided and this application filed October 22, 1928. Serial No. 314,021.

This invention relates to a posting tray and concerns itself primarily with the structure of a drop side for offsetting the sheets and is a division of my copending application, Serial No. 239,882, filed December 14, 1927.

The invention comprises the novel structure and combination of parts hereinafter described and more particularly pointed out 10 and defined in the appended claims.

In the accompanying drawings, which illustrate a preferred embodiment of this invention and in which similar reference numerals refer to similar features in the different views.

Figure 1 is a side elevational view of a posting tray involving this invention.

Figure 2 is an enlarged, transverse, vertical sectional view illustrating the drop side 20 in its lowered position and showing the sheets in offset position.

Figure 3 is an enlarged longitudinal, fragmentary, sectional view taken in a vertical plane just inside of the drop side and looking 25 outwardly.

Figure 4 is an enlarged, transverse, sectional view illustrating the drop side in its lowered position.

Figure 5 is an enlarged fragmentary, elevational view of the drop side, broken away 30 to show the locking means therefor.

Figure 6 is an enlarged, sectional view taken upon the line VI-VI of Figure 5.

Figure 7 is an enlarged sectional view 35 taken upon the line VII-VII of Fig. 3.

The invention is illustrated in connection with a posting tray having corner posts 1, between a pair of which there is a drop side 2 which is hinged at its lower edge to a plate 3 extending between the corner posts 1 and secured to an angle member 4 through a filler plate 5. The drop side 2 of the tray carries a pair of latches 6 and 7 (Figure 5). These latches extend through a suitable hollow space in the drop side and are adapted for engaging apertures in the corner posts 1. The inner ends of these latches 6 and 7 are connected to an operating lever 8 which is pivoted to the drop side by means of a pivot 9 and extends through a slot in the wall of

the hollow space. It will be noted that the latch bolts 6 and 7 are connected to the lever 8 upon diametrically opposite points with respect to the pivot 9, with the result that as the lever is swung in one direction both latch bolts will be simultaneously retracted. A spring 10 surrounds the latch bolt 6 and is confined between a pin 11 on the latch bolt and an abutment 12 on the drop side, with the result that as the latch bolt 6 is retracted, 55 the spring will be compressed. And when the lever 8 is released the spring 10 will project the latch bolt 6 into engagement with the post 1. As the latch bolt 6 is thuswise projected, it will swing the lever 8 and project the latch bolt 7 into engagement with its post. 60

The aforementioned drop side 2 is provided with a swingable abutment 13 which is hinged at a suitable point intermediate the top and bottom of the side as shown in Figures 2 and 4. This swingable abutment 13 is adapted to lie flat against the interior of the drop side when the drop side is in vertical position. When the drop side is in lowered position, the abutment 13 may be swung 70 into vertical position as shown in Figure 2 for limiting the offsetting movements of the sheets. 75

The drop side 2 has an angular member 14 upon each lateral edge (Figure 3). The lower end of each member 14 has a hook-shaped end 15 which extends through an aperture 16 in the bottom of the tray. When the drop side 2 is swung into horizontal position these hook-shaped ends 15 will swing out of the aperture 16 and will hook upon the edges of the posts 1 for supporting the drop side in a horizontal position. To one of the members 14 there is secured a resilient leaf spring 17 80 (Figure 3) and the swingable abutment 13 is provided with a footpiece 18 which has one edge in frictional engagement with the leaf spring 17. When the abutment 13 is swung into vertical position with respect to its side, 85 as shown in Figures 2 and 4, the footpiece 18 will rest against the drop side for maintaining the abutment in vertical position. The spring 17 exercises sufficient pressure on the footpiece 18 to maintain the swingable abutment 100

ment 13 in either operative or inoperative position.

In the use of this tray for posting purposes, it may be desirable to offset certain sheets. In such a case the lever 8 is operated to unlatch the drop side which may then be swung into a horizontal position until the hook-shaped projections 15 engage the inner sides of the posts 1 and support the drop side in horizontal position. The swingable abutment 13, which is in the form of a plate hinged to the inner side of the drop side, may then be swung to the position shown in Figure 2, in which position it is supported against outward swinging movement by the aforementioned footpiece 18. When the posting operation is completed, the sheets may be returned to the body portion of the tray and the drop side may be swung upwardly for automatically engaging the latches with the corner posts for locking the same in a vertical position.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

- 20 1. In a posting tray having a drop side, a plate hinged to said drop side and swingable from a position parallel therewith to a position at right-angles thereto, resilient means on said drop side and a member on said plate cooperating with said resilient means for maintaining said plate in either of its two positions.
- 25 2. In a posting tray having a drop side, a swingable abutment upon the drop side, and cooperating yielding means between said drop side and swingable abutment for controlling the movement of said abutment.
- 30 3. In a posting tray having a drop side, an abutment hinged to said drop side and swingable from a position parallel therewith to a position at right-angles thereto, a foot piece on said abutment adapted for resting upon said drop side when said abutment is at right-angles to said drop side and frictional means between said drop side and foot piece for maintaining said abutment at right-angles to said drop side.
- 35 4. In a posting tray having a drop side, an abutment hinged to said drop, a foot piece upon said abutment for engaging said drop side when said abutment is swung at right-angles to said drop side and a leaf spring on said drop side adapted for engagement by said foot piece for controlling the swinging movements of said abutment.

In testimony whereof I have hereunto subscribed my name at Chicago, Cook County, Illinois.

VICTOR W. GIDEON.
